US0D1098255S

(12) **United States Design Patent** (10) **Patent No.:** **US D1,098,255 S**
Eun (45) **Date of Patent:** **** Oct. 14, 2025**

(54) **POS TERMINAL**

(71) Applicant: **POSBANK CO., LTD.**, Seoul (KR)

(72) Inventor: **Dong-Uk Eun**, Gwangmyeong-si (KR)

(73) Assignee: **POSBANK CO., LTD.**, Seoul (KR)

(**) Term: **15 Years**

(21) Appl. No.: **29/883,304**

(22) Filed: **Jan. 26, 2023**

(30) **Foreign Application Priority Data**

Jan. 13, 2023 (KR) 30-2023-0001564

(57) **CLAIM**

The ornamental design for a POS terminal, as shown and described.

DESCRIPTION

FIG. 1 is a perspective view of a POS terminal, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another perspective view from a different angle thereof.

In the drawings, the broken lines depict portions of the article that form no part of the claimed design.

1 Claim, 8 Drawing Sheets
